UNITED STATES PATENT OFFICE

2,599,161

OVERWINDING PREVENTER

Georges Bridevaux, Tavannes, Switzerland, assignor to Tavannes Watch Co. S. A., Tavannes, Switzerland, a firm of Switzerland

Application April 17, 1951, Serial No. 221,419
In Switzerland December 22, 1950

6 Claims. (Cl. 58—83)

1

This invention relates to a timepiece. This timepiece is characterized by a sliding member to which the winding means imparts a reciprocating movement and on which is mounted a slider which is capable of being displaced on the said member and carries a means for driving the barrel ratchet, this slider being returned by a coil spring intended to yield, when the tension of the barrel spring reaches a given value, in such a way that the ratchet remains stationary even when the displacements of the sliding member continue.

The accompanying drawings illustrate, by way of example, one embodiment of the invention.

Figure 1 is a plan view of a timepiece;

Figure 2 is a section of a detail, on the line II—II of Figure 1; and

Figure 3 is a section on the line III—III of Figure 1.

The timepiece illustrated is a small clock which is wound by means of a crank fixed to the centre of the movement. This crank, indicated by 1, is shown in Figure 3; it is rigid with a hub 2 turning on a journal 3 fixed to a plate 4 which carries all the winding members and is itself fixed to the bridges of the framework. The hub 2 carries a cam 5 co-operating with a pin 6 fixed to a sliding member 7, which is mounted on the plate 4 in such a way as to be capable of undergoing rectilinear displacements. A spring 8 tends to press the pin 6 against the cam 5. The pin 6 is situated on the axis of the member 7, which is guided by a pin 9 passing through a slot 10 in the member 7 and by two screws 11. A slider 12 is arranged in an elongated aperture 13 in the member 7. This slider can be displaced in this aperture; it carries a pawl 14 which a spring 15 presses against a ratchet 16 which forms part of the winding system. The pawl 14 is displaced tangentially to the ratchet 16, so that no force is wasted. The ratchet 16 is rigid with a pinion 17 driving the wheel 18 of a moving member, of which the pinion 19 meshes with the barrel ratchet indicated by 20. All these moving members, with the exception of the barrel ratchet, are carried by the plate 4. The pinion 19 is situated underneath the barrel bridge 21. The pawl 14 is pivoted about a screw 22 engaged in the slider 12 and keeping this slider pressed against a flange 13a of the aperture 13. The sliding member 7 also carries a lever 24 pivoted at 23 by one of its extremities, while to its other extremity is fixed a pin 25 for the attachment of a coil spring 26. The other end of this spring is attached to a corner-piece 27 fixed to the sliding member 7

2

by a screw 28. This corner-piece 27 can be displaced on the member 7, whereby adjustment of the tension of the spring 26 is rendered possible. The lever 24, subjected to the action of the coil spring, acts on an abutment 12a of the slider 12 so as to keep this slider pressed against one extremity of the elongated aperture 13. The axis of the spring 26 is parallel to the direction of the displacements of the slider 12, so that the whole 10 of its strength is used without any loss in lateral components.

When the crank 1 is actuated, the cam 5 acting on the pin 6 displaces the sliding member 7 against the spring 8. A reciprocating movement 15 is then imparted to the member 7, independently of the direction of rotation of the cam 5. While the slider 12 remains in the position shown in Figures 1 and 3, the pawl 14 causes the ratchet 16 to turn in the direction of the arrow 26. As 20 soon as the tension of the barrel spring reaches a given value, if the winding force is greater than the tension of the spring 26 the pawl 14 impinges against the ratchet 16 and the slider 12 is immobilised, the spring 26 yielding when the displacement of the member 7 continues. The slider 12 is then displaced, in the elongated aperture 13, in relation to the member 7. By adjusting the tension of the coil spring 26 it is possible to adjust the maximum tension to which the barrel 30 spring is to be wound.

In the example illustrated the cam is actuated by the crank 1 situated on the outside of the case of the small clock, the back of which is indicated by 30 (Figure 3), but this invention may 35 equally well be applied to watches with automatic winding, in which event the hub 2 could carry an oscillating winding mass situated inside the case.

What I claim is:

1. In a timepiece, a barrel spring, a barrel ratchet, a sliding member, a pin rigid with said member, a rotary cam, a spring acting on said pin to keep it in contact with said cam so that said cam imparts to said sliding member a reciprocating movement, a slider mounted on said sliding member and capable of being displaced on said member, a means carried by said slider for driving said barrel ratchet, and a coil spring returning said slider and intended to yield, when the 45 tension on the barrel spring reaches a given value, in such a way that the ratchet remains immobile even when the displacements of the sliding member continue.
2. In a timepiece, a winding means, a barrel spring, a barrel ratchet, a sliding member to

which said winding means imparts a reciprocating movement, a slider mounted on said sliding member and capable of being displaced on said member, a means carried by said slider for driving said barrel ratchet, a lever pivoted by one of its extremities on said sliding member, and a coil spring attached on the one hand to the other extremity of said lever and on the other hand to said sliding member, said lever bearing against said slider so as to return it to a given position in relation to said sliding member, said coil spring being intended to yield, when the tension on the barrel spring reaches a given value, in such a way that the ratchet remains immobile even when the displacements of the sliding member continue.

3. In a timepiece, a winding means, a barrel spring, a barrel ratchet, a sliding member to which said winding means imparts a reciprocating movement, a slider mounted on said sliding member and capable of being displaced on said member, a means carried by said slider for driving said barrel ratchet, a lever pivoted by one of its extremities on said sliding member, a coil spring attached on the one hand to the other extremity of said lever and on the other hand to said sliding member, said coil spring having its axis parallel to the direction of the displacements of said slider and a device enabling the tension of said coil spring to be adjusted, said lever bearing against said slider so as to return it to a given position in relation to said sliding member, said coil being intended to yield, when the

tension on the barrel spring reaches a given value, in such a way that the ratchet remains immobile even when the displacements of the sliding member continue.

5. Timepiece as claimed in claim 1, in which the displacements of the sliding member are produced by the rotation of the cam in either direction.

10 5. In a timepiece as claimed in claim 1, a case, a crank situated on the outside of said case and driving said cam.

15 6. In a timepiece, a winding means, a barrel spring, a barrel ratchet, a sliding member to which said winding means imparts a reciprocating movement, a slider mounted on said sliding member and capable of being displaced on said member, a means carried by said slider for driving said barrel ratchet, and a coil spring returning said slider and intended to yield, when the tension on the barrel spring reaches a given value, in such a way that the ratchet remains immobile even when the displacements of the sliding member continue, said slider being mounted in an elongated aperture made in said sliding member.

25 GEORGES BRIDEVAUX.
